UNITED STATES PATENT OFFICE

EDWARD G. MEYERS, OF MAPLEWOOD, NEW JERSEY, ASSIGNOR TO M. C. D. BORDEN & SONS, INC., OF NEW YORK, N. Y., A CORPORATION OF NEW YORK

DESIGN FOR A TEXTILE FABRIC

Application filed April 1, 1933. Serial No. 47,661. Term of patent 7 years.

To all whom it may concern:

Be it known that I, EDWARD G. MEYERS, a citizen of the United States of America, and residing at Maplewood, in the county of Orange and State of New Jersey, have invented a new, original, and ornamental Design for a Textile Fabric, of which the following is a specification, reference being had to the accompanying drawing, forming part thereof.

The figure in the drawing is a plan view in full size showing the details of the design.

I claim:

The ornamental design for a textile fabric substantially as shown.

EDWARD G. MEYERS.
